DESIGN FOR A HOUSE SLIPPER

Martha P. Hiestand, Princeton, Wis.

Application June 15, 1945, Serial No. 120,129

Term of patent 14 years

(Cl. D7—7)

To all whom it may concern:

Be it known that I, Martha P. Hiestand, a citizen of the United States, residing at Princeton, in the county of Green Lake and State of Wisconsin, have invented a new, original, and ornamental Design for a House Slipper, of which the following is a specification, reference being had to the accompanying drawing, forming part thereof.

Figure 1 is a perspective view showing my new design of house slipper having a sole and lower body portion shown in full lines, which are the essential features, and the upper shown in dot and dash lines;

I claim:

The ornamental design for a house slipper, as shown and described.

MARTHA P. Hiestand.
